Syvester Orr

UNITED STATES PATENT OFFICE.

SYLVESTER OAR, OF KANSAS, ILLINOIS.

CAR-COUPING.

SPECIFICATION forming part of Letters Patent No. 257,372, dated May 2, 1882.

Application filed January 23, 1882. (Model.)

To all whom it may concern:

Be it known that I, SYLVESTER OAR, a citizen of the United States, residing in Kansas, Edgar county, Illinois, have invented a Safety 5 Car-Coupler, of which the following is a full, clear, and exact description thereof, reference being had to the accompanying drawings and letters of reference marked thereon, in which—

Figure 1 is a side elevation of one end of a 10 car with a part of my improved safety car-coupling applied thereto, and Fig. 2 is a side elevation of my improved car-coupling applied to the ends of two cars.

My invention relates to improvements in 15 car-couplings; and it consists in the peculiar arrangement of the parts, as hereinafter more fully set forth.

In the accompanying drawings, *a* represents a transverse rock-shaft, journaled in the boxes 20 *c*, secured to the end of the car *A*, and provided with collars *d*, secured to the rock-shaft on the outside of the boxes *c*. The outer ends of the rock-shaft *a* are provided with bent handles *b* and a spring, *m*, secured to the end of 25 the car *A*, wound around the rock-shaft *a*, between one of the boxes *c* and an arm, *e*, and the opposite end of the spring *m* is secured to the rock-shaft *a*. The arm *e* is secured to the rock-shaft *a*, and is adapted to engage, when 30 the rock-shaft *a* is turned up, with a hook or catch, *h*, secured to the end of the car *A*.

To the inner end of the shaft *e* is secured a curved arm or bow, *e'*, lying under the shaft *e*, and into the vertical slot, between the arm *e* 35 and curved arm *e'*, projects the pin *k*, secured to one side of the clevis or coupling-link *n*, pivoted by a bolt, *o*, in the top of one of the draw-heads.

p p represent hooks adapted to engage with 40 the outer ends of the clevis or coupling-link *n*.

The outer end of the shaft *e* is provided with an eye, *q*, which engages with a rod, *t*, passing through an eye, *r*, secured to the end of the car *A*. By this construction, by moving laterally the rod *t* or handles *b* the cars can be 45 uncoupled without danger of injury to the operator, whether coupling from the top or sides of the cars, the spring *m* and rock-shaft *a*, provided with the arm *e*, holding the coupling-link or clevis coupled and the latch or hook *h* 50 holding the link or clevis uncoupled.

It will be seen that by this construction the spring *m* performs the double purpose of holding the link coupled and also forcing the rock-shaft and its arm *e* laterally, so that the latter 55 will engage with the catch *h* and hold the link uncoupled.

What I claim as my invention, and desire to secure by Letters Patent, is—

1. The combination, with the pivoted link *n*, 60 provided with the lateral arm *k*, of the rock-shaft *a*, provided with the arms *e e'*, having a slot between them, catch *h*, and spring *m*, performing the double purpose of holding the link coupled, and moving the arm *e* laterally into 65 engagement with the catch to hold the link uncoupled, substantially as described, and for the purpose set forth.

2. The combination, with the car *A*, provided with the catch *h* and boxes *c c*, rock-shaft *a*, provided with handles *b b*, and arms *e e'*, having a slot between them, of spring *m*, secured to the car and rock-shaft, and rod *t*, substantially as described, and for the purpose set forth.

SYLVESTER OAR.
